(57) **CLAIM**

The ornamental design for a flying disk with pet grasping lip, as shown and described.

DESCRIPTION

FIG. 1 is a perspective view of a flying disk with pet grasping lip assembly, showing my new design;

FIG. 2 is a front elevational view thereof, the rear elevational view, left-side elevational view, and the right-side elevational view all being identical thereto;

FIG. 3 is a top plan view thereof;

FIG. 4 is a bottom plan view thereof; and,

FIG. 5 is a cross-sectional view thereof, taken along line 5-5 of FIG. 3.
